CLAIM

We claim the ornamental design for a holder for pen and data storage device, as shown and described.

DESCRIPTION

FIG. 1 is an isometric view of a holder for pen and data storage device showing our new design;

FIG. 2 is a top view thereof;

FIG. 3 is a bottom view thereof;

FIG. 4 is a left side view thereof;

FIG. 5 is a right side view thereof;

FIG. 6 is a front view thereof;

FIG. 7 is a rear view thereof; and,

FIG. 8 is another isometric view thereof.

The evenly spaced broken lines in FIGS. 1, 2, 6, and 8 are included to show portions of the holder for pen and data storage device that form no part of the claimed design. The long and short broken lines in FIG. 8 are included to show articles in the environment that form no part of the claimed design.
